Primary Examiner — Carol P Rademaker(74) *Attorney, Agent, or Firm* — Marshall, Gerstein & Borun LLP; Richard M. LaBarge(57) **CLAIM**

The ornamental design for a bottle, as shown and described.

DESCRIPTION

FIG. 1 is a left side, back, and top perspective view of a bottle that has the design.

FIG. 2 is front, left side, and bottom perspective view of the bottle.

FIG. 3 is a rear elevation of the bottle.

FIG. 4 is a left side elevation of the bottle.

FIG. 5 is a right side elevation of the bottle.

FIG. 6 is a top plan view of the bottle; and,

FIG. 7 is a bottom plan view of the bottle.

The dash-dash-dash-type broken lines shown in the drawings views are included for the purpose of illustrating environmental structure and form no part of the claimed design. The dot-dash-dot-dash-type broken lines shown in the drawing views define the boundaries of the claimed design.
